Primary Examiner—Antoine D. Davis

(74) Attorney, Agent, or Firm—W. Norman Roth

(57) **CLAIM**

The ornamental design for a pressure measurement cartridge for a low and vacuum pressure gas pressure gage, as shown.

DESCRIPTION

FIG. 1 is a perspective view showing the front of our new design;

FIG. 2 is a perspective view showing the rear of our new design;

FIG. 3 is a right side elevation view of our new design;

FIG. 4 is a left side elevation view of our new design;

FIG. 5 is a top view of our new design; and,

FIG. 6 is a bottom plan view of our new design.
